UNITED STATES PATENT OFFICE.

BERNARD A. SCHRODER, OF BIRMINGHAM, ALABAMA, ASSIGNOR TO AUTOMATIC GAS RADIATOR COMPANY, A CORPORATION OF ALABAMA.

GAS HEATING SYSTEM.

1,280,870.

Specification of Letters Patent.

Patented Oct. 8, 1918.

Application filed December 26, 1914. Serial No. 879,109.

To all whom it may concern:

Be it known that I, BERNARD A. SCHRODER, a citizen of the United States, residing at Birmingham, in the county of Jefferson 5 and State of Alabama, have invented certain new and useful Improvements in Gas Heating Systems, of which the following is a specification.

My invention relates to improvements in 10 means for heating houses and buildings by gas burning radiation systems.

One object of my invention is to adapt the 15 gas heating appliances to be inserted in radiators of the type heretofore used with steam and hot water radiation systems without requiring any substantial change in their design or arrangement.

A further and most important object of 20 my invention is to safe guard against the possible opening of the gas valve of any type of gas burning radiation system when the fan for exhausting the gases from the radiators is not in service and this control I effect by a novel and simple means of 25 making the operation of the radiator gas valves responsive to the operation of the prime mover which drives the exhaust fan. I claim this feature broadly. By this arrangement when the prime mover stops and 30 the exhaust fan is out of service, it is not possible for any valve of the radiation system to be opened by the automatic control devices and I preferably so protect the valves from casual manual operation that 35 they cannot be opened under such conditions. As a preferred means for controlling the valves, I utilize a motor generator set, the motor being adapted to drive the exhaust fan and a small generator which supplies current for operating the valves.

A further important feature of my invention is the means by which it is adapted 40 for automatic operation under the control of an adjustable circuit closing thermostat 45 of standard design which may be set for any desired degree of room temperature which it is desired to maintain and which will act in the well known manner to make and break the electric circuits, which control the 50 radiator gas valves, and cut the radiators into and out of service as the temperature rises substantially above or falls substantially below that for which the instrument is set. I provide a magnetically operated gas valve for each radiator and wire all so

that current from the generator will act to open the valves when their respective thermostats close their control circuits and when such circuits are opened by the thermostats the valves are released and close automatically. By this means a radiator is caused to burn only a small part of the time to maintain the room temperature, thereby insuring the economical operation of my system. 60

A further object of my invention is to insure the uniform heating of the several radiator sections by the utilization of a perforated draft pipe or similar means which preferably extends through the several radiator sections and is designed and adapted 70 to produce in each of the several sections a substantially uniform draft to insure the equal radiating efficiency throughout the radiator.

A further object of my invention is to 75 utilize an elongated gas burner which is inserted through the bottom alining openings of the radiator sections and which is supplied with air through a series of air ports provided in the radiator sections to cause a 80 substantially uniform flame in each section.

A further object of my invention is to 85 reduce to its simplest and most compact form the control mechanism for the gas and to mount all parts within an inclosing casing which is small, attractive in appearance, and readily attached to the radiator, thereby making simple and inexpensive the installation of my gas burner equipment.

A further object of my invention is the 90 complete inclosure of the magnetically controlled gas valve within a gas tight casing so that it is protected perfectly from being tampered with and leakage avoided.

A further novel feature of my invention 95 is the provision of a baffle strip to be inserted into the bottom of the radiator sections and to be disposed between the burner tube and the air inlet ports so as to deflect the entering air and cause a better and more 100 uniform combustion along the burner pipe.

My invention further comprises the novel 105 details of construction and arrangements of parts which, in their preferred embodiments only are hereinafter more particularly described and illustrated in the accompanying drawings which form a part of this specification, and in which:

Figure 1 is a view illustrating the piping 110 connections and motor generator set in side

elevation, and one radiator partly in section on the line $x-x$ of Fig. 2 and partly in elevation.

Fig. 2 is a vertical sectional view taken along the line $y-y$ of Fig. 1.

Similar reference numerals refer to similar parts throughout the drawings.

I have shown my invention in connection with a radiator formed by a series of sections 1 but it will be understood that other forms of radiators may be substituted. These radiator sections are substantially of standard form except that to reduce the cost I dispense with nipples between sections and merely face off the bosses 2 so as to make a tight joint when the sections are drawn together in the manner hereinafter described. In each radiator section and preferably at the bottom thereof I provide an air inlet opening 3. The radiator sections are tied together at their upper ends by a perforated draft pipe 4 having its ends threaded and one screwed into a threaded opening in a plug 5 and the other screwed through a plug 6, which plugs fit snugly into and effectively close the radiator end openings. The draft pipe has a series of ports 7 therein which preferably decrease in size gradually as they approach the outlet end of the pipe, to give a uniform draft to each radiator section. The exposed end of pipe 4 is connected by an elbow with the exhaust pipe 8 connecting with a main exhaust pipe 9 of the radiator system, which in turn is connected to the blower 10. The radiator sections are tied together at their lower ends by the burner pipe 11 which is screwed at one end into a plug 5 while its other end is screwed into the reduced end 12 of the gas control casing 14. Square shoulders 13 are provided on the plugs 5 and 6 to receive a wrench. A baffle plate 15 is inserted through the end openings of the radiator sections and extends longitudinally under the burner and over the air inlet holes 3, serving to baffle and distribute the air to the burner 11 so as to obtain a substantially uniform combustion in the several radiator sections.

50 The control casing 14 is shown produced in as simple and compact form as possible and one which is especially designed to prevent the apparatus being tampered with. The casing is preferably formed as an integral angled casting having a chamber 16 in its upper end below which is a diaphragm 17 provided with a central opening through which the inner angled and threaded end of a small pipe 18 is passed. A nut 19 on 55 the pipe engages the under face of the diaphragm and a nut 20, having a taper valve seat in the top of its bore, engages the end of pipe 18 above the diaphragm and serves to hold the pipe in position with the spud 60 21 thereon disposed just beyond the air in-

take opening 22. An adjustable sleeve 23 is slidable over the opening 22 to regulate the supply of air and the pipe 18 is disposed with its discharge opening in alignment with and adjacent to the open end of 70 the burner pipe 11. A gravity seating cone valve 24 is adapted to control the gas supply to pipe 18.

A gas service pipe 25 enters the chamber 16 above the diaphragm 17. From this 75 chamber 16 leads a small pipe 26 having therein a valve casing 27 and a valve 28 which controls the gas supply to the pilot burner 29 which passes through a suitable opening provided therefor in the end radiator section. This section is also provided with an opening 30 for giving access to the pilot to light it. I screw or otherwise make tight and fast in the top of the chamber 16 a metal cap 31 having integral therewith 80 or otherwise suitably connected thereto a core 32 of a magnet 33. The wires for this magnet are connected to the terminals 34 and 35 mounted in insulation plugs 34^a and 35^a seated tight in openings in the cap. 85 These terminals are connected respectively to the leads 36 and 37 of a branch circuit connected in multiple to the wires 38 and 39 of the main control circuit for the whole system. 90

95 Current is supplied to the main control circuit by a small generator 40 which is part of a small and compact motor generator set comprising a motor 41 connected on one side to the blower 10 and on the other side to the generator 40, all parts being mounted upon a suitable bed plate 42. The current is supplied to drive the motor 41 by the service wires 43 and 44 under control of a main house switch 45.

100 In each branch control circuit formed by the leads 36 and 37 for a radiator or a group of radiators, I provide an adjustable make and break thermostat 46 of standard design and which therefore I will not describe in detail otherwise than to state that its pointer arm 47 is adjustable relative to the dial 48 which is marked for the different degrees of temperature which it may be desired to maintain in the room and when the pointer is set for any given degree the thermostat will make and break the circuit connections across its terminals 49 and 50 as the temperature approaches and departs from that designated degree. Of course the 115 thermostat may permit of a substantial departure from the given degree before acting on the circuit. The wire 36 is interrupted and its ends connected to these terminals 49 and 50 with the result that when the circuit 120 is closed by the thermostat the magnet 33 will be energized and its core 32 will raise the cone valve 24 and allow gas to flow through pipe 18 to the mixing chamber in the end of the casing 14 and thence into the 125 130

burner 11. The pilot 29, having been previously ignited, is maintained constantly burning while the heater is under automatic control, and it will ignite the gas as soon as it flows from the perforations in the burner 11. The products of combustion will pass up through the several radiator sections, being drawn in substantially equal volume therethrough and out through the pipe 4 and 10 the exhaust pipe connections 8 and 9 to the blower 10 which discharges it through a pipe or stack 51 to the atmosphere. A water sealed drain pipe 52 having a U-bend is provided at the bottom of the exhaust pipe 9 15 to take care of the water of condensation therein.

It being understood that one or more radiators may be controlled by each branch control circuit 36, 37, that there may be as many 20 of such branch circuits as the house or building to be heated may require, and that the pipes 9 and 25 are connected to each radiator, the operation of my system may be briefly described as follows: By closing the 25 switch 45, service current is supplied to the motor 41 which thereupon drives the blower and the generator. The blower serves through its connections 8 and 9 to exhaust the gas and products of combustion from the 30 radiators and the small generator 40 delivers current through the main control circuit to the several branch circuits 36, 37 under control of their thermostatic regulators 46.

Assuming a regulator to be set for 70° and 35 the temperature of the room to be 60°, the regulator will immediately close the circuit to the magnet 33, and, if the blower and generator are operating, the magnet will open the valve 24 and the radiator will start 40 into service, the burner being ignited by its constantly burning pilot. As the temperature in the room rises the thermostatic regulator responds and when the temperature reaches 70° it automatically breaks the 45 branch control circuit, whereupon the magnet 33 is deenergized and the valve 24 drops by gravity shutting off the gas supply to the radiator and the latter remains out of service until the temperature in the room falls 50 to a predetermined extent, whereupon the regulator will again automatically close the branch circuit and the operation will be repeated. In this manner, my heating system will automatically maintain any desired temperature 55 in any room of the house and by cutting the radiator out of service when the room has been brought to the desired temperature, I obtain a very great economy in the consumption of gas, for by actual tests I 60 have found that the gas under ordinary weather conditions burns only a small fraction of the time. My system requires but a small blower sufficient to insure the exhaust of the gas and products of combustion from 65 radiators connected thereto, no other duty

being required of the blower, and hence it can be driven with but small power. By connecting both blower and generator to the same motor, I positively prevent the possibility of any radiator in a system becoming ignited when the blower is off because there would be no current to open the valves, and when the blower is on no explosion can result.

A perforated cover plate 53 may be provided for the opening 30 through which the pilot burner 29 is ignited. I attach this plate by screws to the radiator so that it can be removed, but it generally remains in place as the pilot burner is intended to burn 80 while the radiation system is in service.

Having thus described my invention, what I claim as new and desire to secure by Letters Patent, is:—

1. In a gas burning radiation system, a 85 gas heated radiator, a gas control valve therefor, suction means to exhaust gases from the radiator, electric valve operating means for the gas valve, and a common source of power for actuating said suction 90 means and energizing the valve operating means.

2. In a gas burning radiation system, a gas heated radiator, an electrically controlled gas supply valve for said radiator, 95 a fan and suction connections therefrom to the radiator, and a motor generator set which drives the fan and supplies current to operate said valve.

3. In a heating system comprising a plurality of independent gas burning radiators, each having a gas supply valve, electric means to operate the valves, thermostatic means which control the operation of the valves, power driven means to exhaust gases 100 from the radiators, and a motor generator set comprising a generator which supplies current to said electric means and a motor connected to said generator and to said power driven exhaust means for the system. 105

4. In a gas burning radiation system, in combination, a motor generator set, a fan blower driven by said motor generator, and an electric circuit system supplied with current by said motor generator set and adapted to control the opening of radiator gas supply valves, gas burning radiators, and a suction pipe system connected to said fan and to the several radiators for the purpose of exhausting the gases from the latter. 110

5. In a gas burning radiation system, a gas burning radiator, a gas valve therefor, electric apparatus to operate said valve, a thermostatic means to automatically control the operation of said electric apparatus, a 115 power driven suction apparatus connected to the radiator, and a common motor to drive the electric and suction apparatus.

6. In a gas burning radiation system comprising radiators which are grouped for 120 125

unit control, an exhaust piping system and motor driven means coöperating therewith to carry off the products of combustion from said radiator, electric means to control the supply of gas to the radiators of each unit, said means being in a branch control circuit, a common control circuit with which each branch circuit connects, means automatically responsive to the stoppage of said motor driven means to break said common control circuit, and an automatic control means for

each branch circuit comprising an automatic temperature-responsive means adapted to be set for different temperatures and to make and break the branch circuit that it controls, 15 substantially as described.

In testimony whereof I affix my signature in presence of two witnesses.

BERNARD A. SCHRODER.
